UNITED STATES PATENT OFFICE.

WILLIAM H. McCULLOUGH, OF CHICAGO, ILLINOIS.

LIGHTNING-CONDUCTOR.

No. 852,572.

Specification of Letters Patent.

Patented May 7, 1907.

Application filed November 1, 1906. Serial No. 341,524.

To all whom it may concern:

Be it known that I, WILLIAM H. McCULLOUGH, a citizen of the United States, residing at Chicago, in the county of Cook and State of Illinois, have invented certain new and useful Improvements in Lightning-Conductors, of which the following is a specification.

This invention relates to improvements in electrical conductors of the class commonly termed "lightning rods", and more particularly to the formation of the connecting joints between two or more rods or sections of the woven wire or cable form.

The especial advantages secured by my invention are economy of time and labor in making the connections, and greater efficiency as electrical conductors obtained in that abrupt or sharp corners or angles are avoided, provision is made for expansion and contraction of the conductor wires at the joints, and ample contacts are provided for the continuous flow of the electrical force or "current".

In the accompanying drawing which forms a part of this application:—Figure 1 is an elevational view of a terminal or point and its connected line conductor, as erected. Fig. 2 is a fragmentary view on an enlarged scale showing my improved method of forming a connection between a terminal and a line conductor or between vertical and horizontal lines; Fig. 3 is an end view at 3 of Fig. 4 slightly magnified; Fig. 4 is a fragmentary view showing the connection or splice between two lines.

As will be seen from the drawing, my improvement pertains to the hollow or tubular woven-wire conductors, in which a plurality of copper-wires are more or less loosely interwoven to form a tube as 8. These wires are so arranged that each constitutes a working line or conductive unit, and at the same time, provision is made for incidental contraction and expansion due to extremes of cold and heat. Because of the ductility of the copper wires and the fact that they are loosely interwoven, I am able with a very simple tool to press aside the wires at any given point and thus form an opening in the woven walls of the tube, large enough to receive the end of a separate conductor as 9 or 10 preferably contracting the inserted end to facilitate its passage through such opening, and for a short distance, into the con-

ductor so open. Ordinarily the frictional contact between the inserted portion of the one section and the enveloping portion of the connected section, will be sufficient to maintain the connection, but if desired, some of the wires of the inserted section may have their ends bent outwardly and inserted between the wires of the outer section as at 13, or separate tie wires may be used.

To secure the main line conductor suitable clips 7 may embrace it and be fastened by nails or otherwise to the adjacent portion of the building as 5.

In the drawing I have shown a connection embodying a horizontal or main line conductor 12, a terminal line conductor 9, and a bracing and coupling section 10. The conductor 12 is opened at two points to receive the lower ends of the terminal 9 and the coupling 10, and the terminal is opened to receive the upper end of the coupling section thus effecting connections at three points.

It is manifest that the insertion of one conductor section in another, will tend to stiffen the rod at the joint so formed, and thus promote the strength and rigidity of the conductor. It will also be apparent that by increasing the number of wires at such joints greater conductivity will be obtained, whereas, the joints when secured by metallic bands or coupling pieces either cast or stamped, offer more or less obstruction to the flow of the electric current and hence impair the efficiency of the entire conductor. The method of connecting the line and branch wires or rods above described may be adopted wherever a joint is presented, and lends itself peculiarly to gradual or wide bends or angles, forming in effect, a continuous, unbroken and homogeneous conductor.

Having thus described my invention what I claim is:—

1. An electrical conductor consisting of two or more sections each composed of a woven-wire tube, one of said sections having an opening in the side and the other section having its end inserted in said opening.

2. An electrical conductor consisting of two or more sections of woven-wire tubing connected together, the end of one section being inserted through the wall of the other section and the ends of the wires of the inserted section being bent about the wires of the receiving section.

3. An electrical conductor consisting of a

line rod formed of wires woven to form a tube, terminals each consisting of wires woven to form a tube, the ends of said terminals connected with said line rod by inserting same through suitable openings formed in the walls of the line rod, and braces or coupling sections joining said terminals with said line rod, said coupling sections formed of wires woven to form a tube and having their ends

inserted through suitable openings formed in the walls of the line rod and the terminal rods.

In testimony whereof I affix my signature in presence of two witnesses:

WILLIAM H. McCULLOUGH.
